UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

MOTOR.

Application filed September 30, 1921. Serial No. 504,449.

To all whom it may concern:

Be it known that I, MARTIN NYSTROM, a citizen of the United States, residing at Chicago, in the county of Cook and State of Illinois, have invented certain new and useful Improvements in Motors, of which the following is a specification.

The object of this invention is to provide a simple and compact motor for phonographs which will include all the features found necessary to practical service, and which can be cheaply and easily manufactured.

Another object of the invention is to produce a motor in which adjustments and repairs can be readily and quickly made.

Another object of the invention is to so arrange the parts that they can be assembled in a very small, light frame, or supporting structure, and be readily accessible for replacement or repair.

Other and more specific objects of the invention will become apparent as the description is read in connection with the accompanying drawing illustrating a selected embodiment of the invention, in which—

Fig. 1 is an inverted plan view of the motor made according to my invention;

Fig. 2 is a longitudinal section on the line 2—2 of Fig. 1;

Fig. 3 is an elevation looking at the left end of Fig. 1;

Fig. 4 is an elevation looking at the right end of Fig. 1; and

Fig. 5 is a perspective view of a part of the ratchet mechanism.

Referring to the drawing and the reference characters thereon, 10 indicates a top plate to which the frame 11 of the motor is secured by the bolts 12. A longitudinal shaft 13 is supported in the standards 14 and 15 along the middle of the frame, and is held in place by a locking screw 16 or other suitable means. The hubs 17, 18 and 19 are loosely journaled on shaft 13, and the hubs 17 and 19 are equipped with gears 20 and 21 respectively. The inner end of a spiral spring 22 is secured to the hub 17 in any suitable manner, as by the screw 23, and has its outer end fixed as by the rivet 24 to the rim 25 of a drum 26, having its hub 27 rotatably mounted on the bearing 28 of the

hub 17. The drum 26 is connected by a bayonet joint 29, or other suitable device with a drum 30 having its hub portion 31 fastened to the hub 18. The inner end of a spiral spring 32 is fixed to the hub 18 by the screw 33 and its outer end is secured to a rim 34 of a drum 35 having a hub 36 journaled on a bearing 37 on the hub 18. The rim 34 is connected to a rim 38 of a drum 39 by a bayonet joint 40, or other suitable device, and the hub portion 41 of the drum 39 is journaled on a bearing 42 on the hub 19. The outer end of a spring 43 is secured to the rim 38 and its inner end is secured to the hub 19 by a screw 44. A spacer 45 is suitably supported between the springs 32 and 43. By this arrangement all of the springs may be wound by rotating the gear 20 and all of the springs will drive the gear 21. The result is that the jumping and other irregularities incident to spring motors is to a large extent eliminated and a spring length is provided that will drive the motor for a comparatively long period.

The winding mechanism includes the pinion 46 meshing with the gear 20 and fixed to a shaft 47 journaled in the standard 15 and equipped with a ratchet wheel 48 adjacent to the threaded portion 49 on which a winding crank may be secured. A pawl 50 pivoted at 51 is equipped with teeth 52 adapted to engage the corresponding teeth 53 of the ratchet wheel 48, and prevent reverse movement of the shaft 47. A U-shaped friction clip 54 straddles the ratchet wheel 48 and is pivoted at 55 on the pawl 50. The wings 56 and 57 of the clip 54 are arranged to frictionally engage the sides of the ratchet wheel 48 and may be corrugated or otherwise roughened to provide the necessary resistance to relative movement. The wing 57 is equipped with an extension 58 adapted to contact with a pin 59 to limit the movement of the clip 54 when the ratchet wheel 48 is rotated. In operation, the crank or other device is applied to the shaft at 49 and the ratchet wheel 53 is rotated. A frictional engagement between the wheel and the wings 56 and 57 causes the clip to move upwardly in Fig. 3 carrying with it the free end of the pawl 50. Upon a slight reverse movement of the wheel, the clip 54 will pull the pawl downwardly into

engagement with the ratchet. This construction is very quiet, and at the same time, very effective.

The gear 21 meshes with a pinion 60 on a shaft 61 journalled in bearings 62 and 63 in the standards 64 and 65 respectively. The bearings 62 and 63 are threaded in the standards and are adjustable to take up play in the shaft. Set screws 66 and 67 serve to lock the bearings in adjustment. The standard 65 has an obliquely arranged arm 68 in which the lower end of the vertical spindle 69 is journalled, the upper end being mounted in a suitable bearing 70 in the frame. This spindle is equipped with a worm 71 adapted to mesh with a worm wheel 72 on the shaft 61 by which the spindle may be driven from the springs above described. The upper end of the spindle is suitably constructed to receive a record table not shown.

In order to control the speed of the spindle 69, I provide a governor of the centrifugal type which is driven from a worm wheel 72 on the spindle 69 which meshes with a worm 73 on the governor shaft 74 journalled in bearings 75 and 76 in standard 65 and the standard 77 respectively. These bearings are also threaded to the standards 30 and are locked in place by suitable set screws. Loosely journalled on shaft 74 is a sleeve 78 having a collar 79 at one end and carrying a drum 80 at the opposite end. The web of the drum 80 is equipped with suitable slots through which are passed springs 81 secured at one end to the collar 79 and at the opposite end to a collar 82 rigid with the shaft 74. Each spring is equipped with a weight 83. In operation, the centrifugal force causes the weights 83 to move outwardly, and thereby move the drum 80 downwardly in Fig. 1. A brake pad 84 is located adjacent to the drum 80 and is made adjustable so as to be frictionally engaged with the drum when the motor tends to exceed a particular speed. I prefer to mount the pad 84 on a screw 85 threaded to an arm 86 of the lever 87 pivoted on a bolt 88 and having an arm 89 engaged with the control mechanism 90. The control mechanism includes a knob 91, an indicator finger 92, and a fixed dial 93. After the mechanism has been properly adjusted, the knob may be turned until the indicator is aligned with a particular speed of revolution for the table, and the governor will limit the motor to that speed.

In the manufacture of mechanical motors of this type for phonographs, it is very desirable to have the parts very compactly arranged and in such position that every element likely to require any adjustment may be readily accessible. Also, it is very desirable to make the organization such that the entire assembly will occupy a compara-

tively small space and can be mounted in a light, open frame. By arranging a series of springs as shown on a shaft lying substantially in the middle of the frame, locating the governor shaft transversely to the frame and across one end, and mounting the spindle between the governor shaft and the springs, a very compact motor is obtained. The drum of the governor shaft being close to the bottom of the frame as shown in Fig. 2 permits the use of a short lever arm for carrying the pad 84 as compared with the long arm 89 by which the control is effected. By making the frame or supporting structure of a generally flat, rectangle equipped with standards to provide bearings for the various shafts, practically every part of the entire assembly is open to inspection while in place, and the bearings for all the shafts are readily accessible for adjustment or replacement. Furthermore, any one of the shafts can be readily removed in its entirety without dismantling the other parts of the machine. The use of the arm 68 on the end of the standard 75 eliminates all cross pieces at the bottom of the frame that would interfere with access to the lower portion of the motor.

I am aware that changes in the form and proportion of parts, and in the details of construction of my invention may be made without departing from the spirit or sacrificing any of the advantages thereof, and I reserve the right to make all such changes as fairly fall within the scope of the following claims.

I claim:

1. In a device of the class described, a frame, a standard substantially midway between the sides of the frame and spaced from one end, a second standard adjacent to the opposite end and aligned with said first standard, a horizontal shaft supported by said standards, a series of driving springs mounted on said shaft, a winding mechanism adjacent to said second standard, a gear connected with said springs adjacent to the first standard, a third standard at one side of the frame and at the end opposite the second standard and having an obliquely disposed arm to support an upright spindle, a spindle journalled in said frame and said arm and provided with a gear, a fourth standard aligned with said third standard and located adjacent to said springs, a second horizontal shaft journalled in said third and fourth standards, a pinion on said shaft meshing with the gear connected with the springs and a gear on said shaft meshing with the gear on said spindle, a fifth standard aligned with said third standard and adjacent to the opposite side of the frame, a governor shaft supported by said third and fifth standard, gearing between said gover-

- nor shaft and said spindle, a governor on said governor shaft including a brake drum, a brake lever pivoted to said frame, and a brake carried by said lever and adapted to 5 co-operate with said drum.
2. In a device of the class described, a frame, a pair of standards arranged centrally with respect to said frame, a shaft mounted in said standards, a series of 10 springs mounted on said shaft, a gear connected with said springs at one end, a vertical spindle journaled in the frame adjacent to said gear, reduction gearing be-
- tween said spindle and said gear, a governor including a transversely arranged shaft, a 15 pair of standards on which said governor shaft is journaled, one of said standards being equipped with an arm extending towards said springs and provided with a bearing for one end of said spindle, a drum mounted 20 on said governor shaft, a brake adapted to co-operate with said drum, a lever pivoted to said frame and carrying said brake, and means for adjusting said lever.

MARTIN NYSTROM.
